UNITED STATES PATENT OFFICE.

GEORGE A. KERESTES, OF PITTSBURGH, PENNSYLVANIA, ASSIGNOR TO NOVELTY AMUSEMENT CO., OF PITTSBURGH, PENNSYLVANIA, A CORPORATION OF DELAWARE.

TARGET APPARATUS.

Application filed December 18, 1918, Serial No. 287,341. Renewed October 10, 1923.

To all whom it may concern:

Be it known that I, GEORGE A. KERESTES, a citizen of the United States, residing at Pittsburgh, in the county of Allegheny and 5 State of Pennsylvania, have invented certain new and useful Improvements in Target Apparatus, of which the following is a specification.

The present invention relates to improvements in target apparatus designed for use 10 in connection with moving picture and stereopticon machines and the like, and more particularly to that class of apparatus in which a picture is projected upon a perforable screen behind which is a target adapted, on the impact of a bullet or projectile, to make electrical connections whereby means responsive to said impact are employed for controlling the operation of the picture projecting device or the like.

Apparatus of this class is shown in a patent granted to me October 8, 1918, No. 1,281,169; in the said patent I have shown an embodiment employed with a moving 15 picture machine. In the present invention, I show an embodiment including a stereopticon machine, but it is evident that my invention as herein disclosed may be utilized in combination with a moving picture machine.

In machines of the class to which my invention relates and in target apparatus in which electrical currents are employed, considerable trouble has heretofore been encountered due to the unsatisfactory target 20 per se and its connections, and one of the prime objects of the present invention is to provide a target or impact receiving means and connections of simple and efficient construction whereby the disadvantages now present are obviated.

In the accompanying drawings which illustrate an application of my invention,

Fig. 1 is a part elevational and a part sectional view particularly showing a perforable screen and a target against which the projectiles or bullets are adapted to strike;

Fig. 2, an enlarged sectional view showing a portion of the target and an electrical switch in connection therewith;

Fig. 3, an elevational view of the portion shown by Fig. 2;

Fig. 4, a sectional detail particularly showing, in connection with the target, the 55 main operating switch;

Fig. 5, an elevational view of the switch mechanism shown by Fig. 4;

Fig. 6, a detail perspective view of a plate entered into the construction of the target;

Fig. 7, a rear elevational view of the target;

Fig. 8, a sectional view taken on line 8—8 of Fig. 7;

Fig. 9, a perspective detail view; and

Fig. 10, a diagrammatic view.

As shown in the drawings, I employ two stereopticon machines A and B of any suitable type, these machines being designed to project pictures upon a perforable screen C, 70 the latter being disposed in advance of a target D. In the particular form of apparatus shown, it is the intention to project a picture upon the screen by means of one of the stereopticon machines, for instance, a 75 picture of an enemy soldier, and have the marksman attempt to strike a predetermined point (bull's eye) on the picture. Should this point be struck, means are provided for cutting off the light to one machine and 80 turning on the light to the other stereopticon machine, thereby instantaneously changing the projected picture of the soldier into another picture of any character contained on the plate of the second machine.

Means are also provided, actuated by the impact of the bullet, for indicating when the picture is hit at some point other than the "bull's eye." As illustrated, these means include a colored shutter adapted to be 85 thrown across the projected picture, thus changing the color of the picture on the screen. It is evident that other means for indicating the hits may be employed.

The target D and its supporting structure, 90 as illustrated and as preferred, comprises a metallic framework including the front uprights 1, inclined vertically extending rear members 2, and horizontally extending members 3 connecting the front and rear members. The inclined members 2 are connected by a series of cross angle bars 4. Angle bars 4 are designed to support a number of independently movable overlapping metallic plates 5.

The form of the plates 5 is particularly shown by Fig. 6, and, as shown, each comprises an upper cutaway portion and a pair of upwardly projecting apertured lugs 6. Plates 5 are loosely suspended from the 110

angle bars 4 in a slightly inclined position by means of pins 7, one end of each pin extending through an opening in bar 4 and its other end through an aperture 8 in the lug 6. Said plates 5, being suspended in the manner shown, are each adapted to be moved inwardly the desired distance upon impact of a bullet, and after said inward movement, to swing back, due to gravity, to their normal inclined positions; these positions being shown by Fig. 1. Each plate 5 is provided with an inwardly projecting push rod 9 and a plate engaging hook member 10, said hook member being adapted to engage an adjacent plate. The function of member 10 is to prevent the plates swinging forward to a vertical position or beyond a vertical plane, thus preventing an inward movement of a plate except when it is effected by the impact of the bullet.

11 designates a vertically extending switch operating rod carrying thereon a contact member 12. Contact member 12 is adapted to cooperate with switch mechanism 13 (see Fig. 5). Extending at right angles with rod 11 and across the target, I employ a number of loosely mounted bars 14 each having rigidly secured thereto a plurality of light plates 15.

Each plate 15 is disposed in the line of travel of the rod 9 of a plate 5, consequently, when one of the plates 5 is moved inwardly, rod 9 will come into contact with a plate 15 moving said plate sufficiently to cause the bar 14 to be tilted for the purpose of raising the switch operating rod 11. In addition to the plates 15, bars 14 also carry a vertically extending row of angular plates 15^a. These latter plates are each formed with a bifurcated portion adapted to straddle rod 11 and to engage pins 16 carried on said rod 11.

From the construction just described, it will be understood that upon an inward movement of plate 5, due to the impact of a bullet, rod 11 will be raised sufficiently to complete an electrical circuit for the purpose of effecting certain predetermined operations.

In the particular embodiment of my invention, an upward movement of rod 11 brings contact member 12 into position to complete the circuit to relay or solenoid 16^a thereby moving core 17 inwardly, its opposite end being connected with switch 18 by means of arm 18' and a fiber link construction 19. 20 designates a spring pressed arm designed to hold core 17 in its inward position. Closing the circuit as thus described energizes solenoid 21, causing its core 22 to be drawn upwardly until the upper end of the core 22 strikes against the arm 20, thereby releasing core 17 which is drawn back to its opposite position by means of a spring 23, thus dis-connecting current to

solenoid 21. The movement of core 22 actuates rods 24 to effect a movement of a sliding bar 25. Sliding bar 25 is provided with slots 26, and 27 designates pins on which the bar is mounted.

28 designates a colored shutter adapted to be moved over and away from the machine A for the purpose of changing the color of the projected picture on the screen C. The movement of this shutter is controlled by the movable bar 25 and the connections between said bar and the core 22. The shutter is provided with a pin 29 designed to make contact with an offset 30 on the end of said bar 25. The shutter is also provided with a notch 31 which is adapted to engage an end of a pivoted spring controlled arm 32, whereby the shutter is maintained in position before the light a predetermined length of time. Bar 25 also carries a sliding contact arm 33 which is adapted to slide upon a fiber block 34 having a metallic contact plate 35. 36 designates a guide which prevents arm 33 coming into contact with the plate 35 until the return movement of said arm.

Means for controlling the descent of core 22 are provided, and, as shown, they include a small oil pump structure 37, said pump structure acting as a timer to determine the period of time the shutter is disposed over the machine A. The timer or oil pump may be adjusted by the screw rod 38 which latter controls the movement of the oil within the pump.

A movement of the bar 25 in the opposite direction closes the circuit to the curtain or screen solenoid 39 for the purpose of moving the screen C slightly. This is effected by means of the arm 33 coming into contact with plate 35, thereby completing the circuit. This movement also causes the end of arm 32 to be removed from the notch 31 of shutter 28, and as the shutter is weighted, it will move away from its position over the light into the position shown in Fig. 10. The function of shutter 28, which is a colored shutter of any suitable material, is to change the color of the picture projected on to the screen C when a bullet strikes the target.

As heretofore stated, under the application of my invention as shown, the marksman attempts to hit a particular spot on the screen or curtain. Directly behind the predetermined spot on the curtain, I employ an element which, when struck by the bullet, actuates means to close an electric circuit for the purpose of switching the light from one stereopticon machine to the other, thereby producing, when the "bull's eye" is hit, an immediate change of pictures.

The means shown for accomplishing this end include a push rod 40 mounted and adapted to move in a casing 41. Rod 40 at

one end is provided with the element 42; the opposite end of rod 40 is adapted, when forced backward by the bullet, to strike a pivoted plate 43, said plate in turn being 5 adapted to move arms 44, which latter are pivotally supported on a rod designed to be moved slightly by the plate 43 (see Fig. 3). Each arm 44 has a contact point adapted to be moved into engagement with 10 contact points on switches 45 and 45^a. Spring 46 interposed between the head and an end of the casing causes the push rod to move back into normal position immediately after the circuit to a solenoid 47 is closed, 15 and a spring 46^a draws the plate 43 together with its arms 44 back to their normal position. A completion of the circuits just mentioned moves core 48 and the connected switch arm 49 sufficiently to shift the contact 20 from contact point 50 to contact point 51 of said switch 52, thereby cutting off light to machine A and turning on the light to machine B. Machine B is designed to project a different picture from the picture projected 25 by machine A.

Simultaneously with the completion of the circuit to solenoid 47, a circuit is completed to solenoid 16^a through switch 45^a for the purpose of energizing solenoid 21 to control 30 the time it is desired to have the picture from machine B thrown onto the screen.

It will be understood that the timer 37 is employed for this purpose, also that when core 48 is drawn towards solenoid 47, a 35 pivoted spring controlled arm 53 holds the core in position until released by the action of lever 54, the latter being fixedly secured to shutter or screen 28, the movement of said arm 54 being effected by the movement of 40 the sliding bar 25. 55 designates the spring connected with arm 53 and 56 a spring having one end secured to arm 49 and designed to normally maintain the said arm and core 48 outwardly and away from solenoid 47.

45 What I claim is:

1. The combination with a picture projecting machine, of a target including a plurality of overlapping loosely suspended plates adapted to be moved by the impact 50 of a bullet, and means including a tilttable bar, a vertically movable switch actuating element, and connections between said element and the tilttable bar actuated by the movement of a plate for controlling the operations of the picture machine.

2. In target apparatus for use with picture projecting machines, a picture projecting device, a perforable screen, a target back of the screen, and means actuated by the 60 impact of a bullet on the target for changing the color of the picture on the screen.

3. In target apparatus for use with picture projecting machines, a picture projecting device, a perforable screen, a target back 65 of the screen, and means actuated by the

impact of a bullet on the target for changing the color of the picture on the screen, said means including an electric circuit, a shutter, and mechanism for moving the shutter rendered active by closing said electric circuit. 70

4. In target apparatus, a target including a plurality of loosely suspended impact plates disposed in inclined planes, an electric circuit, a switch mechanism, an electric contact means actuated by the movement of an impact plate, said contact means common to a plurality of impact plates and cooperating with the switch mechanism to make and break the circuit. 75

5. In target apparatus, a target having a plurality of overlapping loosely suspended plates disposed in inclined planes and adapted to be moved by the impact of a bullet, means carried by one plate and 80 cooperating with an adjacent plate for preventing the plates swinging into vertical positions, a normally inactive electric circuit connected with the target, and mechanism actuated by the movement of a plate 90 for rendering the said electric circuit active.

6. In target apparatus, a target having a plurality of overlapping loosely suspended impact plates, a plurality of movable cross bars having plate members thereon, a rod carried by an impact plate and adapted upon the impact of a bullet to move one of the plate members and its bar, a vertically movable rod having pins, means on said cross bars for engaging said pins, a switch mechanism, an electric contact member on the vertically movable rod arranged to be moved into and out of contact with the switch to make and break an electric circuit. 95

7. In target apparatus, a target including a plurality of overlapping loosely suspended and inclined impact plates, means carried by the plates for preventing the plates swinging into vertical positions, an electric switch mechanism, common electric contact means for a plurality of plates interposed between the impact plates and the switch and actuated by the movement of an impact plate 100 to close an electric circuit. 110

8. In target apparatus, a target including a plurality of overlapping loosely suspended and inclined impact plates, loosely mounted cross bars having projecting elements rigidly secured thereto, means carried by an impact plate for striking a projecting element of a cross bar, an electric switch mechanism, means interposed between the impact plates and the switch and actuated by the movement of an impact plate, said latter means including a vertically movable rod having 115 a contact member coacting with the switch mechanism to make and break an electric circuit. 120

9. In target apparatus, a target having a loosely suspended impact plate, a switch 130

mechanism, and means interposed between the impact plate and switch mechanism to make and break an electric circuit, said means including a vertically movable rod 5 carrying an electric contact member, and elements actuated by the movement of the impact plate for moving said rod.

10. In target apparatus, a target including a loosely suspended impact plate, a movable cross-bar carrying a plate member, a rod carried by the impact plate and adapted upon the impact of a bullet to strike the plate of the cross-bar to tilt the latter, a switch mechanism, and means actuated by 15 the movement of the cross-bar and cooperating with the switch to make and break an electric circuit.

11. In target apparatus, a target including a loosely suspended impact plate, a movable cross-bar carrying a plate member, means on the impact plate adapted upon

impact of a bullet to strike the plate of the cross-bar to tilt the latter, a switch mechanism, and means including a vertically movable rod actuated by the movement of the cross-bar and cooperating with the switch to make and break an electric circuit. 25

12. In target apparatus, a target including a plurality of suspended impact plates, an electric circuit, a switch mechanism, a common electrical contact device actuated by the movement of an impact plate and cooperating with said switch mechanism to make and break the circuit. 30 35

In testimony whereof, I affix my signature in presence of two witnesses.

GEORGE A. KERESTES.
